MOUNTING BASE FOR A TAPE DISPENSER

Edward Waltz, Grand Rapids, Mich., assignor to E. O. Bulman Manufacturing Company, Inc., Grand Rapids, Mich., a corporation of Michigan

Filed Mar. 16, 1961, Ser. No. 64,345

Term of patent 14 years

(Cl. D74—1)

Fig. 1

Fig. 2

The broken line showing of the tape dispenser in FIGURE 1 is merely for the purpose of illustration.

I claim:

The ornamental design for a mounting base for a tape dispenser, as shown and described.
